LEVEE

Winfield Dorn, Chico, Calif.

Application September 21, 1936, Serial No. 101,854

2 Claims. (Cl. 61—30)

This invention relates to levee constructions, and more particularly to a levee construction which may be readily erected in a relatively short time, and which will withstand the pressure of water under flood conditions and also withstand any erosion from the swiftly flowing water.

An object of this invention is to provide an improved levee construction which embodies elements that are in the main readily obtainable at short notice and which may be so combined as to provide a permanent levee.

Another object of this invention is to provide in a levee means between the earth fill and the water to prevent the swiftly moving water from wearing the fill away.

A further object of this invention is to provide in a levee construction a compacted means in the form of bales of material which is interposed between the earth fill and the water, the bales of material serving to prevent washing of the fill, and at the same time providing a means which will gradually become filled with sand and dirt so that no tiny rivulets will seep through the bales and effect erosion of the earth fill.

At the present time it is well known that emergency levees are thrown up with sand bags placed between the earth fill and the water, but these levees are only of temporary construction, and frequently the spaces between the various bags will admit water into the earth fill and thus gradually wear the fill away. It is, therefore, a still further object of this invention to provide a levee which may be erected as a temporary or emergency expedient and then left in position as a permanent adjunct.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a perspective view, partly broken away, of a levee constructed according to an embodiment of this invention.

Figure 2 is a transverse sectional view taken through the levee.

Figure 3 is a sectional view taken through a modified form of this invention.

Referring to the drawing, the numeral 10 indicates the ground level of the shore line along a body of water, such as a river or the like, and the numerals 12 and 13 designate the natural embankments beside the water above the low ground

level 10 at the upstream and downstream end of the levee to be hereinafter described.

A plurality of longitudinally spaced apart posts 11 are sunk into the ground along the shore line, the posts 11 being sunk to such a depth 5 that they will readily stand upright under considerable pressure. Preferably the bottoms of the posts 11 are embedded in concrete 14 or the like which is poured into the holes 15 provided for the posts 11. The concrete will retard 10 rotting of the bottoms of the posts 11 and will also assist in firmly supporting the posts 11 in an upright position.

A wire screen 16 of suitable construction is secured by staples or other fastening devices to the 15 shore side of the posts 11, and this wire screen 16 is preferably of relatively heavy construction so that relatively heavy objects floating in the water and striking the screen will not materially damage the screen. A trench 17 is dug inwardly of 20 the posts 11 and the wire 16, and in this trench 17 there are placed a plurality of bales 18, the bales 18 being placed end to end, and then additional bales or bundles superposed upon each other until the desired height is obtained at the outer or river 25 side of the levee. It will be understood that the posts 11 and the screen 16 may be of sufficient height so that the water under extreme flood conditions will not flow over the top thereof, and the height of the bales may be made substantially 30 level with the top of the posts 11 and the wire screen 16.

Reinforcing or anchoring logs 19 are disposed inwardly of the posts 11 and the bales 18, these logs 19 being disposed in a horizontal position 35 within or at the rear of the fill. The logs 19 are connected to the front or outer posts 11 by means of wire strands 20 or the like, the strands 20 being wrapped around the posts 11 and logs 19 and stretched to the desired degree so that the pressure of the earth fill 21 which engages against the inner or shore side of the bales 18 will not force the bales 18 and the posts 11 outwardly or in the direction of the water. The reinforcing or anchoring logs 19 are particularly desirable during the construction of the fill 21 so that the heavy trucks, tractors or the like which are used in conveying the fill will not force the soft dirt or fill outwardly toward the screen 16, the logs 19 serving to equalize the distribution of pressure. 40 The fill 21 engages about the wire strands 20, and the top of the fill 21 is preferably substantially 45 level with the top of the bales 18.

At the upstream end of the levee a plurality of boards or planks 22 are secured to the posts 50

55

11, and at this end of the levee bales 18 may also be positioned inwardly of the boards 22. Preferably the boards 22 are positioned on an obtuse angle to the outer side of the levee, the angle extending inwardly toward the shore so that no water from the river will be able to flow behind the fill. These boards 22 also act as an abutment or breakwater to prevent any floating object from damaging the upper end of the levee.

10 The lower end of the levee is constructed somewhat similar to the upper end, being provided with a board facing 23 which extends inwardly from the stream. At this lower end of the levee the bales 18 may if desired be omitted.

15 In Fig. 3 there is disclosed a modified form of this invention which may be used where there is a fairly high embankment along the shore and it is desired to prevent the flood waters from wearing away the embankment. In this form the 20 posts 11' are embedded in the ground in the usual manner with their lower ends embedded in concrete if desired. The posts 11' are positioned in outwardly spaced relation to the embankment 24, and wire screen 16' is secured to the inner sides 25 of the posts 11'. The space between the screen 16' and the outer side of the embankment 24 is then filled with superposed bales 18'.

The earth fill 21 is preferably of such a depth as to adequately withstand the pressure of the 30 flood water against the outer side of the levee and in this manner the wire fence with the filtering means 18 will not be bent over by the pressure of the water. The wire strands 20 preferably engage over the tops of certain of the bales 35 18 so that the bales 18 will not rise or float when the water rises on the outer side of the levee. The bales 18 are also held against rising by pressure of the fill 21 against the inner sides thereof.

As the water in the river rises to flood condition 40 and engages the levee, the water will of course soak the bales 18, but the bales 18 will then swell to more closely compact the material thereof. It is, of course, well known that waters in flood condition are muddy, containing sand, dirt 45 and other foreign matter. As this murky water enters the bales 18 the solid matter in the water will gradually fill up any hollow spaces in the bales 18 so that these bales will soon become relatively solid with solid matter. The screen 16 will 50 not only prevent the bales 18 from moving outwardly and into the stream, but will also act as a perforate reinforcing wall for the levee and a protecting wall therefor. The force of the water will be dissipated within the bales 18 so that no 55 moving water will contact with the fill 21. For this reason the fill 21 need not be of such solid construction as to prevent passage of water therethrough, and may thus be constructed of rocks, gravel, sand or any other material which is available for this purpose.

With the subsiding of the flood waters the bales 18 will be found to be impregnated with sand, mud or other relatively fine particles which were

in the flood waters, so that after one or more flood periods the bales 18 will gradually lose their identity as such, and the rotting of the bales 18 will not materially affect the condition of the outer side of the levee as the screen 16 will firmly hold 5 the material against erosion.

It will be noted from the drawing that only a single tier or series of superposed bales 18, or 18', has been shown, but it will be understood that if desired any number of tiers of bales 18 or 18' may 10 be used. As an example, assuming that the bank 24 is away from the shore line a distance greater than a single tier of bales 18', and that it is difficult to obtain sufficient material to fill in the space between the bales 18' and the bank 24, then 15 any number of tiers of bales 18' may be placed between the wire 16' and the bank 24, and if there is any likelihood that these bales 18' may float away such bales may be staked down with wires, weighted with stones, or otherwise held in 20 proper position. After the levee has been in use for some time, and in the event any of the bales 18 become loose or begin to disintegrate, such bales may be readily replaced with new bales. These bales 18 and 18' are preferably formed of 25 straw or like material which can be obtained very cheaply and quickly.

It is obvious that various changes and modifications may be made in the details of construction and design of the above specifically described embodiment of this invention without departing from the spirit thereof, such changes and modifications being restricted only by the scope of the following claims:—

What is claimed is:

1. A levee comprising a plurality of vertically disposed spaced apart posts, a concrete base engaging about the lower end of each of said posts, a perforate fence structure secured to said posts, a plurality of fibrous bale members disposed in superposed position along one side of said fence structure, an earth fill contacting with said bale members inwardly of said fence structure, wires secured at one end to certain of said posts and extending in the direction of said fill, said wires engaging over the tops of certain of said bale members, and anchoring means mounted in said fill and connected to the opposite ends of said wires. 45

2. A levee comprising a plurality of vertically disposed spaced apart posts embedded at their lower ends in the ground, a perforate fence structure secured to said posts, a plurality of pervious block members formed of compressed fibrous material disposed in superposed relation and engaging against the inner face of said fence structure, an earth fill engaging against said block members and extending inwardly thereof, and anchoring means embedded in said fill and connected to said posts, said anchoring means engaging over certain of said block members to hold 60 said block members against vertical movement.

WINFIELD DORN.
